US0D1107529S

(12) **United States Design Patent** (10) **Patent No.:** **US D1,107,529 S**
(45) **Date of Patent:** **** Dec. 30, 2025**

(54) **FLOOR CUTTER**

(71) Applicant: **INDUSTRIAL SUPPLY (QINGDAO) LTD.**, Qingdao (CN)

(72) Inventor: **Wensheng Xu**, Shandong (CN)

(**) Term: **15 Years**

(21) Appl. No.: **35/523,612**

(22) Filed: **Dec. 5, 2024**

(80) **Hague Agreement Data**

Int. Filing Date: **Dec. 5, 2024**

Int. Reg. No.: **DM/243164**

Int. Reg. Date: **Dec. 5, 2024**

Int. Reg. Pub. Date: **Jan. 17, 2025**

(51) **LOC (15) Cl.** **08-03**

(52) **U.S. Cl.**

USPC **D8/51**

(58) **Field of Classification Search**

USPC **D8/14, 51, 98; D15/127, 129**

CPC **B26D 1/085; B26D 1/045; Y10T 83/741**

See application file for complete search history.
